ANIMATED DECORATIVE LAMP

Aubrey B. Leech, Los Angeles, Calif., assignor to Econo-lite Corporation, Los Angeles, Calif., a corporation of California

Application June 24, 1955, Serial No. 36,672

Term of patent 7 years

(Cl. D48—20)

Fig. 1

Fig. 2

Fig. 3

Fig. 4

I claim:

The ornamental design for an animated decorative lamp, substantially as shown and described.
